CLAIM

The ornamental design for shoe with ornament, as shown and described.

DESCRIPTION

FIG. 1 a perspective view of a shoe with ornament, showing my new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a rear elevation view thereof;

FIG. 7 is a front detail view thereof, showing the ornament removed from the shoe for illustrative purposes; and,

FIG. 8 is a rear detail view thereof, showing the ornament removed from the shoe for illustrative purposes.

The broken lines in the figures illustrate portions of the shoe with ornament that form no part of the claimed design.
